UNITED STATES PATENT OFFICE

169,900

LIFT TRUCK

Joseph A. Frischmann, Cleveland Heights, Ohio

Application May 16, 1951, Serial No. 15,198

Term of patent 14 years

(Cl. D14—3)

To all whom it may concern:

Be it known that I, Joseph A. Frischmann, a citizen of the United States, residing in Cleveland Heights, in the county of Cuyahoga and State of Ohio, have invented a new, original, and ornamental Design for a Lift Truck, of which the following is a specification, reference being had to the accompanying drawings, forming a part thereof wherein:

Fig. 1 is a side elevational view of a lift truck showing my new design;

Fig. 2 is a front elevational view thereof a portion of the broken line representation of the lifting element being cut away to show the front of the truck body;

Fig. 3 is a rear elevational view of the lift truck; and

Fig. 4 is a perspective view of the lift truck.

The side of the truck opposite to the one shown in Fig. 1 is the same as illustrated in Fig. 1.

The characteristic features of my design reside in the portions shown by means of full lines in the drawing.

I claim:

The ornamental design for a lift truck, as shown and described.

JOSEPH A. FRISCHMANN.
